TENSION-CONTROLLING MEANS FOR TRAVELING OFFSET WEBS

Application filed March 21, 1930. Serial No. 437,819.

In rotary multicolor web perfecting printing presses where a traveling offset web is passed around the impression cylinder of the second printing unit under the printed web, it has been difficult to obtain clean and sharp printing.

If this tension on the offset web, necessary to the proper rewinding thereof, be eliminated where the offset web is in contact with the impression cylinder, the offset web and the printed web will travel together around the impression cylinder, thereby ensuring clean and sharp printing by the second printing unit.

The object of my invention is to accomplish this result by providing automatic means for maintaining a predetermined amount of slack in and tension on the offset web between the impression cylinder of the second printing unit of the printing press and the tension control rolls of the offset web tension controlling mechanism for the rewinding mechanism.

The means which I have shown for accomplishing this result includes a variable speed electric motor independent of the driving means for the printing press, said motor being utilized for driving the offset web tension control rolls and the rewinding rolls at the desired speeds, the speed of the motor being controlled by the position of the offset web slack roll through a suitable controller in the motor circuit.

In practice, the travel of the printed web per cylinder revolution varies with the different forms used on the form cylinders, thus making it practically impossible to properly proportion the tension control rolls of the offset web controlling mechanism so that they will travel with the offset web under all conditions. It is to prevent this variation from disturbing the travel of the offset web on the impression cylinder that I interpose the means for automatically maintaining a predetermined amount of slack in and tension on the offset web between the impression cylinder of the second printing unit and the said tension control rolls.

A practical embodiment of my invention is represented in the accompanying drawings,

in which the form and impression cylinders of the second printing unit are denoted by 1, 2 and 3, which cylinders are driven in the usual manner. The traveling printed web is denoted by 4 and it is shown as being led around the idler roll 5 to and around the impression cylinder 3 and from thence to and beyond the idler roll 6. The traveling offset web is denoted by 7 and it is shown as leading from its supply roll over the idler rolls 8 to and around the impression cylinder 3 and under the printed web 4. From thence the offset web is shown as passing around the positively driven guide roll 9 and under the slack roller 10 where the slack in the web is formed, to and around the positively driven tension control rolls 11, 12 and 13 of the offset web tension controlling mechanism. From thence the offset web passes around the idler rolls 14, 15 and 16 to the take-up roll 17 which rests upon and is driven by the rewinding rolls 18, 19 of the offset web rewinding mechanism.

The guide roll 9 is shown as being driven from the impression cylinder gear 20 at substantially the surface speed of the impression cylinder through the train of gears 21, 22, 23, 24, 25.

The tension control rolls 11, 12 and 13 of the offset web tension controlling mechanism are shown as driven from a variable speed electric motor 26 entirely independent of the driving means for the printing press. In the present instance these tension control rolls 11, 12 and 13 are driven in unison through the gears 27, 28, 29. The rewinding rolls 18, 19 are driven from the tension control rolls at a slightly greater surface speed than the surface speed of the tension control rolls from the gear 29 through the train of gears 30, 31, 32, 33, 34. The tension control rolls and thereby the rewinding rolls are driven from the motor 26 in the present instance through a belt and pulley connection 35, 36, 37 between the motor and tension control roll 12.

A predetermined amount of slack in the offset web between the second printing unit and the tension controlling mechanism is au- 100

tomatically maintained by varying the speed of the motor 26 and thereby the surface speed of the tension control rolls 11, 12, 13, as follows:

5 The offset web slack roller 10 is mounted in a rocking support 38, to which support one end of a sprocket chain 39 is attached, which chain passes over a sprocket 40 on the shaft 41 and is provided at its other end with a weight 42 for substantially counterbalancing the weight of the roller 10 and its rocking support. A gear 43 is fast on the shaft 41 and meshes with a pinion 44, fast on the shaft 45, which carries the arm 46 of a controller or 10 15 20 25 30 rheostat 47 which is located in the electric circuit, denoted by 48, of the motor 26.

The predetermined tension is maintained on the offset web slack between the second printing unit and the web tension controlling mechanism as follows:

20 A roller 49 bears on the offset web as it passes over the first tension control roll 11, with sufficient pressure to eliminate any slippage of the web as it passes through the web 25 30 35 40 45 tension controlling mechanism. As the only tension exerted on the web slack is formed by the pressure of the web slack roller 10 thereon, this tension can be easily regulated by increasing or diminishing the effect of the counterbalanced weight 42 on the said roller.

The operation is as follows:

As the normal slack in the offset web increases, the slack roller 10 will drop; thereby, through the chain, sprocket and gearing, 35 cause the rheostat arm 46 to travel over its contact points in a direction to speed up the motor 26 and thereby increase the surface speed of the tension rolls 11, 12 and 13, and also correspondingly increase the surface 40 45 50 55 60 speed of the rewinding rolls 18, 19. As the extra slack in the offset web is taken up, the rheostat arm 46 returns to its previous normal position in which the motor 26 is driven at substantially the speed of the press. Reversely, as the normal slack in the web decreases, the slack roller 10 is raised, thereby causing the rheostat arm 46 to travel over its contact points in a direction to reduce the 65 70 75 80 85 90 95 100 105 110 115 120 125 130 surface speeds of the tension control rolls 11, 12, 13 and the rewinding rolls 18, 19, until the normal slack in the offset web is obtained and the contact arm 46 returned to its normal intermediate position.

From the above description it will be seen that a predetermined amount of slack and tension may be automatically maintained in and on the offset web at all times, thereby ensuring clean and sharp printing by the second printing unit.

It is evident that various changes may be resorted to in the construction, form and arrangement of the several parts without departing from the spirit and scope of my invention, and hence I do not intend to limit

myself to the particular embodiment herein shown and described, but

What I claim is:—

1. In a multicolor web perfecting printing press, a printing unit, a traveling offset web, a web tension controlling mechanism, an offset web rewinding mechanism, and automatic means for maintaining a predetermined amount of web slack and tension thereon between the printing unit and tension controlling mechanism, said automatic means including a variable speed motor for driving both the web tension controlling mechanism and the offset web rewinding mechanism. 70 75 80 85 90 95 100 105 110 115 120 125 130

2. In a multicolor web perfecting printing press, a printing unit, a traveling offset web, a web tension controlling mechanism, an offset web rewinding mechanism driven therefrom, and automatic means for maintaining a predetermined amount of web slack and tension thereon between the printing unit and tension controlling mechanism. 80 85 90 95 100 105 110 115 120 125 130

3. In a multicolor web perfecting printing press, a printing unit, a traveling offset web, a web tension controlling mechanism, an offset web rewinding mechanism driven therefrom, and automatic means for maintaining a predetermined amount of web slack and tension thereon between the printing unit and tension controlling mechanism, said automatic means including a variable speed motor for driving the web tension controlling mechanism and thereby the offset web rewinding mechanism. 90 95 100 105 110 115 120 125 130

4. In a multicolor web perfecting printing press, a printing unit, a traveling offset web, a web tension controlling mechanism, an offset web rewinding mechanism driven therefrom, and web slack controlled means for automatically maintaining a predetermined amount of slack in and tension on the offset web between the printing unit and tension controlling mechanism. 100 105 110 115 120 125 130

5. In a multicolor web perfecting printing press, a printing unit, a traveling offset web, a web tension controlling mechanism, an offset web rewinding mechanism, and automatic means for maintaining a predetermined amount of slack in and tension on the offset web between the printing unit and tension controlling mechanism, said automatic means including a variable speed motor for driving both the web tension controlling mechanism and the offset web rewinding mechanism. 110 115 120 125 130

6. In a multicolor web perfecting printing press, a printing unit, a traveling offset web, a web tension controlling mechanism, an offset web rewinding mechanism, and automatic means for maintaining a predetermined amount of slack in and tension on the offset web between the printing unit and tension controlling mechanism, said automatic means including a variable speed motor for driving both the web tension controlling mechanism 120 125 130

and the offset web rewinding mechanism and also including a web slack roller for controlling the speed of the motor.

7. In a multicolor web perfecting printing press, a printing unit, a traveling offset web, a web tension controlling mechanism, an offset web rewinding mechanism, and automatic means for maintaining a predetermined amount of slack in and tension on the offset web between the printing unit and tension controlling mechanism, said automatic means including a variable speed motor for driving both the web tension controlling mechanism and the offset web rewinding mechanism and also including a web slack roller and a rheostat operated thereby for varying the speed of the motor.

8. In a multicolor web perfecting printing press, a printing unit, a traveling offset web, a web tension controlling mechanism, an offset web rewinding mechanism driven therefrom, and automatic means for maintaining a predetermined amount of slack in and tension on the offset web between the printing unit and tension controlled mechanism, said means including a variable speed motor for driving the web tension controlling mechanism and thereby the offset web rewinding mechanism.

9. In a multicolor web perfecting printing press, a printing unit, a traveling offset web, a web tension controlling mechanism, an offset web rewinding mechanism driven therefrom, and automatic means for maintaining a predetermined amount of slack in and tension on the offset web between the printing unit and tension controlled mechanism, said automatic means including a variable speed motor for driving the web tension controlling mechanism and thereby the offset web rewinding mechanism and also including a web slack roller for controlling the speed of the motor.

10. In a multicolor web perfecting printing press, a printing unit, a traveling offset web, a web tension controlling mechanism, an offset web rewinding mechanism driven therefrom, and automatic means for maintaining a predetermined amount of slack in and tension on the offset web between the printing unit and tension controlled mechanism, said automatic means including a variable speed motor for driving the web tension controlling mechanism and thereby the offset web rewinding mechanism and also including a web slack roller and a rheostat operated thereby for varying the speed of the motor.

11. In a multicolor web perfecting printing press, a printing unit, a traveling offset web, web tension control rolls, offset web rewinding rolls driven therefrom, and web slack controlled means for automatically maintaining a predetermined amount of slack in and tension on the offset web be-

tween the printing unit and the tension control rolls.

12. In a multicolor web perfecting printing press, a printing unit, a traveling offset web, web tension control rolls, offset web rewinding rolls driven therefrom, and web slack controlled means for automatically maintaining a predetermined amount of slack in and tension on the offset web between the printing unit and the tension control rolls, said means including a variable speed motor for driving the tension control rolls and thereby the web rewinding rolls. 70

13. In a multicolor web perfecting printing press, a printing unit, a traveling offset web, web tension control rolls, offset web rewinding rolls driven therefrom, and web slack controlled means for automatically maintaining a predetermined amount of slack in and tension on the offset web between the printing unit and the tension control rolls, said means including a variable speed motor for driving the tension control rolls and thereby the web rewinding rolls and also including a web slack roller for controlling 80 the speed of the motor. 85

14. In a multicolor web perfecting printing press, a printing unit, a traveling offset web, web tension control rolls, offset web rewinding rolls driven therefrom, and web slack controlled means for automatically maintaining a predetermined amount of slack in and tension on the offset web between the printing unit and the tension control rolls, said means including a variable speed motor for driving the tension control rolls and thereby the web rewinding rolls and also including a web slack roller and a rheostat operated thereby for varying the speed 90 of the motor. 95

In testimony, that I claim the foregoing as my invention, I have signed my name this 14th day of March, 1930.
